Primary Examiner — Melanie Pellegrini

(57) **CLAIM**

The ornamental design for a finger ring for an electronic vaporizer, made of any material for a ring and custom design, as shown and described.

DESCRIPTION

FIG. 1 is a rear elevational perspective view of the finger ring for an electronic vaporizer, shown in use of my new design.

FIG. 2 is a top plan view thereof;

FIG. 3 is a bottom view thereof;

FIG. 4 is a right side view thereof, and the left side being a mirror image thereof; shown in use.

FIG. 5 is an exploded view thereof; and,

FIG. 6 is another rear elevational perspective view, without the broking lines form no part of the claimed design.

The broking lines form no part of the claimed design.

1 Claim, 6 Drawing Sheets
